UNITED STATES PATENT OFFICE

156,934

FLOOR RACK, DISPLAY STAND, OR SIMILAR ARTICLE

Edward A. Burgess, Toronto, Ontario, Canada

Application May 1, 1948, Serial No. 146,128

Term of patent 3½ years

(Cl. D33—8)

To all whom it may concern:

Be it known that I, Edward A. Burgess, a citizen of the Dominion of Canada, resident of the city of Toronto, in the Province of Ontario, Dominion of Canada, have invented a new, original, and ornamental Design for a Floor Rack, Display Stand, or Similar Article, of which the following is a specification, reference being had to the accompanying drawing, forming part thereof.

Fig. 1 is a perspective view of a floor rack, display stand, or similar article, showing my new design, and

Fig. 2 is a side view thereof.

I claim:

The ornamental design for a floor rack, display stand, or similar article, as shown.

EDWARD A. BURGESS.
